JULIUS TRÜMPER, OF TEMPELHOF, GERMANY.

BOOKBINDING APPARATUS.

1,131,877.

Specification of Letters Patent. Patented Mar. 16, 1915.

Application filed March 3, 1913. Serial No. 751,937.

To all whom it may concern:

Be it known that I, JULIUS TRÜMPER, a subject of the German Emperor, and residing at Tempelhof, near Berlin, Germany, have invented certain new and useful Improvements in Bookbinding Apparatus, of which the following is a specification.

This invention relates to a device for finishing the rounded corners of book covers, posters, pictures or the like by means of flexible material extending over said corners, the material being folded over on the inside of the covers or on the back of the pictures and posters respectively.

An object of the invention is to provide a device of the character described wherein means are provided for evenly pulling outstanding portions of a flexible material over the rounded corner of a plate and to hold said material in engagement with the plate until it is secured thereto.

Another object of the invention is to provide a device which will firmly engage the cover of a book or the like and which will simultaneously draw a part of a flexible material in diagonal direction toward the holding element, while another part is pressed against the surface of the cover.

Another object of the invention is to provide a device wherein the means for pulling the flexible material over the corner of the book cover is automatically released from engagement with said material when the device itself is lifted from the cover, or when the pressure with which said device is forced against the cover is released.

With these and other objects in view I have illustrated an embodiment of the invention in the accompanying drawing in

which—

Figure 1 is a side elevation of the device. Fig. 2 is a top plan view of the base-plate for the device, a book cover with the cloth on the same being shown in position on the base-plate in dotted lines. Fig. 3 is a vertical section diagonally through the presser of the device taken on line 3—3 of Fig. 4. Fig. 4 is a bottom plan view of said presser. Fig. 5 shows the pulling rod in side elevation, and Fig. 6 is a perspective view of the presser foot.

The device comprises a base-plate 1 preferably provided with beveled edges as indicated at 2 in Fig. 2. A spring 3 is secured to the flat top surface of the base-plate by means of screws 4 or the like and has tend-

ency to press upwardly any material placed on the top surface of the base-plate. An angular stop indicated as a whole at 5 is mounted on the base-plate 1 and comprises two rectangular walls 6 and 7 which are recessed at their intersection, to form a vertical gap 8 for a purpose which will be described below.

Means for securing flexible material to a rounded corner of a book cover, or any other plate are illustrated in Figs. 1 to 3. A presser 9 of substantially square cross section has one rounded corner 10 to fit into the fillet 11 of the angular stop 5 on the base-plate 1. This presser also contains a foot having a plate 12 and pins 13 whereby it is guided in vertical direction in suitable bores or apertures of the foot. The foot plate 12 is pressed normally away from an offset portion 14 at the bottom of the presser 9 by means of a spring 14' acting against the top surface of the plate and inserted in a hole, extending from the bottom of the presser upwardly. The foot plate 12 is secured against being expelled by the spring 14' from the presser 9 by means of a screw 15 which projects into one of the bores for the pins 13. The pins are provided with a longitudinal recess 16 and one shoulder 17 of the recess serves, when in engagement with screw 15 for limiting the inward movement of the foot plate, while the other shoulder 18 limits the outward movement thereof. When the presser 9 is moved downwardly in guiding engagement with the angular stop it will press the foot plate 12 resiliently against the top surface of a cover placed on the base-plate, said top surface preferably being the inner surface of the cover when the binding is complete. In the downward movement of the presser the foot plate 12 will approach gradually the recessed bottom surface 14 of the presser. The projecting part 19 of the bottom surface extends from the rounded corner of the presser along the edges which in the movement of the same remain in engagement with the angular stop.

A pulling rod 20 is slidably held in diagonal direction within the presser 9. It is movably mounted within a bore 21 which extends from the lower rounded corner of the presser upwardly to the front wall thereof. The upper end of the guiding aperture 21 for the pulling rod 20 is closed by means of a screw plug 22 which has a bore

permitting the reduced end 23 of the rod 20 to project therethrough. A spring 24 is interposed between the lower surface of the screw plug 22 and a shoulder 25 formed on the rod. The pulling rod also is provided with a plurality of recesses. One of the recesses, 26, extending in axial direction serves for limiting the downward movement of the pulling rod with respect to the presser 9 for preventing said rod from being expelled from the guiding aperture by the spring 24. For this purpose a pin 27 extends diagonally through the presser 9 in a horizontal plane, intersecting however, the guiding bore 21 of the pulling rod. When the spring 24 presses the pulling rod downwardly the transverse pin 27 engages one shoulder of the recess 26, as shown, and thereby limits the downward movement of the same. On a portion of the pulling rod which is diametrically opposite the recess 26 and closer to the lower end of the rod another recess 28 is cut into the rod and the locking device indicated as a whole by 29 serves for holding the rod in its uppermost position. This locking device includes a spring controlled pin 30 guided in an oblique bore 31 of the presser. This pin is provided near its lower end with a collar 32 and a spring 33 engages said collar, the other end of the spring resting against the inner bottom surface of a hollow nut 34 which closes adjustably the oblique aperture 31 in the pressure device. The movement of the pin is controlled by an arm 35 secured to the projecting end of the pin and carrying a transverse pin 36 which projects through a depending end of said arm. The pin 30 projects into the recess 28 of the pulling rod when the pressure device is in engagement with the inner surface of the book cover. The forward edges of the recess 8 are cut away as indicated at 40 providing recesses in which the transverse pin 36 may operate as the presser 9 is moved downwardly from the position shown in Fig. 1. It will be seen, however, that the upper portions of the edges just mentioned are not cut away to any marked extent and these upper portions of the forward edges of the recess 8 serve as cam surfaces 40' which contact with the pin 36 when the presser 9 is lifted from the position shown in Fig. 1, thus forcing the pin 36 and pin 30 outwardly, for a reason which will later appear.

The operation of the device is about as follows: The principal object of the apparatus is to secure the corner of a cloth cover or the like to the corner of a board; the board X is provided on one side of the same with a cover of cloth or some similar material as indicated at Y. The marginal portions of this cloth are folded over the marginal portions of the board X as indi-

cated at y'. The cloth Y and the marginal portions y' may be secured to the board X by means of an adhesive. The apparatus now serves for folding over the corner portion z' over the corner of the board X and to pull the corner portion z' in diagonal direction so that this corner portion will overlie smoothly the corner portion of the board X. The board X with the cloth applied thereto is therefore placed on the base plate, as indicated in Fig. 2, whereby the corner of the board X engages the fillet 11 of the stop 5. The presser 9 is then forcibly moved downwardly, while being held in engagement with the wall portions 6 and 7 of the stop 5 as indicated in dotted lines in Fig. 2. The foot plate 12 of the presser 9 will engage the marginal portions y' of the cloth cover Y, also as shown in Fig. 2. In the continued downward movement of the presser 9 the lower end of the pulling rod 20 will engage the inturned portion z' of the cloth by means of the prongs 37 at the lower end of the rod 20. Owing to this engagement and the downward movement of the presser, the rod 20 will be forced upwardly in the bore 21. While the rod 20 is moved upwardly in its bore with respect to the descending presser 9, the distance between the lower front end of the rod 20 from the corner of the presser 9 is increased from the distance indicated in Fig. 3 by d to the distance d'. The prongs 37 do not release their hold on the corner portion z' while the presser is moved downwardly and the board X is also prevented from moving since it is being pressed against the plate 1 by the foot 12. The cloth of the corner portion z', therefore will also be pulled inwardly in diagonal direction and the application of this corner portion to the book-cover is performed by a single downward movement of the presser in contra-distinction from the known methods in which this corner portion was applied manually and by a rather tedious operation only. The arm 36 of the locking device 29 is forced into engagement with the cam portions 40 of the walls at the gap 8 of the angular stop. The pressure of the spring 33 acts on the collar 32 of the pin 30 and this pin also carries the element 35 in which the arm 36 is mounted. When therefore the presser 9 is withdrawn from the base-plate 1 upwardly, this arm 36 slides on the concave cam portions 40 and withdraws the pin 30 from the recess 28. In the downward movement, however, this pin may project into this recess owing to the concave wall portions 40 which admit of an inward movement of the arm 36.

The presser 9 may be inserted in a punch press or a book-binding machine and is provided therefore at its upper portion with an aperture 42 and a ledge 41. A bolt, not shown, may be inserted through the apér-

ture 42 and may connect the presser with the reciprocating element of the machine, not shown. The spring 3 on the base-plate lifts the board X as soon as the presser 9 is moved upwardly.

5 I claim:

1. A device for making book covers comprising in combination, vertically movable means for pressing a strip against the board to be covered with the strip, means for pulling the strip over the board at the corner of the board, and releasable means for holding the pulling means.

10 2. A device for making book covers comprising in combination, a support for the work, movable means for pressing a strip against the cover board at one corner, means engaging the strip and pulling it while the pressing means acts on it, and means whereby the engagement of said pulling means is controlled by the movement of said pressing means.

15 3. A device for making book covers comprising in combination, an angular stop for defining the position of the board the corner of which is to be covered by a strip, a presser guided in said angular stop, a pulling rod diagonally disposed within said presser, and means within said presser for 20 resiliently forcing said pulling rod in a diagonal direction downwardly.

25 4. A device for making book covers comprising in combination a base-plate supporting the board to be covered by a corner strip, a presser, a foot plate mounted in said presser and adapted to engage marginal portions of said corner strip and a pulling rod adapted to engage other portions of the corner strip, said pulling rod being mov- 30 ably mounted in an oblique direction within said presser, whereby the rod is shifted parallel to itself in the vertical movement of said presser.

40 5. A device for making book covers comprising in combination a base-plate supporting a board to be covered by a corner strip, a presser, a foot-plate resiliently mounted within said presser for engaging the board and marginal portions of the corner strip, a pulling rod obliquely disposed within said presser whereby the rod is shifted parallel to itself in the vertical movement of said presser, said pulling rod being in engagement with other portions of 45 the corner strip.

50 6. A device for making book covers comprising in combination a base plate supporting a board to be covered by a corner strip, an angular stop defining the position of a corner of said board, a presser guided by said angular stop, a foot plate resiliently mounted on said presser for engaging said board and marginal portions of said corner strip, means for limiting the movement of 60 said foot plate with respect to the presser,

and a pulling rod obliquely disposed within said presser whereby the rod is shifted parallel to itself when the presser is moved in a vertical direction, said pulling rod being in engagement with another portion of the 70 cover strip.

7. A device for making book covers comprising in combination, a base plate supporting a board to be covered by a corner strip, an angular stop on said base plate for defining the position of the corner of the board, a presser guided by the angular stop, a foot plate resiliently mounted within said presser for engaging said board and marginal portions of the corner strip, a pulling rod obliquely disposed within said presser whereby the rod is shifted parallel to itself in the vertical movement of the presser, said pulling rod being in engagement with another portion of the corner strip, and means disposed within said presser for normally forcing the pulling rod downwardly with respect to the presser.

8. A device for making book covers comprising in combination a base plate supporting a board which is to be covered by a corner strip, an angular stop on said base plate defining the position of the corner of the board, a presser in guiding engagement with said angular stop, a foot plate mounted in said presser and engaging marginal portions of the corner strip, a pulling rod angularly disposed within said presser and arranged to engage another portion of the corner strip, means for normally forcing 90 said pulling rod downwardly with respect to the presser, and means for limiting the downward movement of the pulling rod with respect to the presser.

9. A device for making book covers comprising in combination a base plate for supporting the board to be covered by a corner strip, an angular stop mounted on said base plate, a presser in guiding engagement for vertical movement with said angular stop, 105 a foot plate mounted in said presser, a pulling rod angularly disposed within said presser, means for normally forcing said pulling rod downwardly in the presser, the arrangement being such that said pulling rod is pressed inwardly with respect to the presser by the downward movement of the presser when the pulling rod is in engagement with another portion of the cover strip, and releasable means for holding said 110 pulling rod against said first mentioned means.

10. A device for making book covers comprising in combination a base plate for supporting a board to be covered by a corner strip, an angular stop on said base plate defining the position of the corner of the board, a presser in engagement with the angular stop, a pulling rod within said presser and mounted at an angle to the direction of 125 130

movement of said presser and means disposed within said presser for resiliently forcing the pulling rod downwardly in the presser, the arrangement being such that 5 said pulling rod is forced inwardly by the downward movement of the presser when the lower end of the rod is in engagement with a portion of the corner strip, and releasable means for holding said rod against 10 said resilient means.

11. A device for making book-covers comprising in combination a base plate supporting a board to be covered by a corner strip, an angular stop provided with a vertical gap mounted on said base plate and arranged to define the position of a corner of the board to be covered, a presser guided by said stop, a pulling rod angularly disposed with respect to said presser for en-

gaging a portion of the corner strip and 20 inclined away from the angle of said stop, means for normally forcing the pulling rod downwardly, said pulling rod being forced away from said stop by the downward movement of the presser with respect to the board when the pulling rod is in engagement with a portion of the corner strip, resilient means for holding said pulling rod at the limit of its movement and means in engagement with the walls of the gap in 30 the angular stop for releasing said last named means.

In testimony whereof I affix my signature in presence of two witnesses.

JULIUS TRÜMPER.
